UNITED STATES PATENT OFFICE.

WILLIS R. WHITNEY, OF SCHENECTADY, NEW YORK, ASSIGNOR TO GENERAL ELECTRIC COMPANY, A CORPORATION OF NEW YORK.

SUPPORT FOR FILAMENTS.

1,105,050.

Specification of Letters Patent.

Patented July 28, 1914.

Application filed June 14, 1907. Serial No. 378,932.

To all whom it may concern:

Be it known that I, WILLIS R. WHITNEY, a citizen of the United States, residing at Schenectady, county of Schenectady, State of New York, have invented certain new and useful Improvements in Supports for Filaments, of which the following is a specification.

Metal lamp filaments of tungsten, molybdenum, and other high melting metal are, during normal use, subject to expansion and contraction by heating, and furthermore, are sometimes subject to progressive contraction during a considerable portion of their normal life. These lamp filaments are relatively soft and plastic when running at high incandescence, and therefore, should be supported to prevent sagging when the lamp is burned in a horizontal position. Owing to the change in length of the filament, as above mentioned, this supporting means should preferably be resilient in character.

My present invention comprises means for supporting such filaments in an improved manner, whereby the danger of contaminating the filament or the vacuum is obviated, and whereby the filament may be protected against breakage during transportation.

According to my invention, the supporting means consists of or comprises a member of refractory metal, such as tungsten or molybdenum, which may be resilient.

Two embodiments of my invention are illustrated in the accompanying drawing, in which—

Figure 1 is a single filament lamp having a helical tungsten support for the filament loop; Fig. 2 is a multiple filament lamp in which a single tungsten spring serves for all the filaments; and Fig. 3 is a perspective view of a simple apparatus suitable for shaping tungsten wire into the helices illustrated in Figs. 1 and 2.

Tungsten as ordinarily obtained is in the form of a dark powder, very refractory in character, and possessed of so little coherence that it can be shaped into wires only by special treatment. One method of consolidating the tungsten powder into strong coherent wires is described in British Patent #16,530 of 1907 and in applications Serial Nos. 316,005 and 316,006 filed May 9, 1906 and 377,781 filed June 7, 1907 by William D. Coolidge, and I have hereinafter described one method of rendering these wires ductile

and pliant, and of shaping them into forms suitable for use according to my invention. The treatments and manipulations of tungsten hereinbefore referred to and herein-after described are to be considered as also applicable to molybdenum, and the latter is to be regarded as the equivalent of tungsten for the purposes here set forth.

The wire produced as described in the patents and applications aforesaid is found to be strong and firm and somewhat elastic, but without the capability of taking a permanent set and practically devoid of ductility, at least in the sense in which that term is applied to such metals as copper, silver, platinum, etc. To shape such a coherent body of non-ductile tungsten into a helix, I may make use of the simple apparatus illustrated in Fig. 3, comprising a platinum mandrel 1 supported in a wooden block 2 and heated by a flame 3 burning at the end of a glass tube 4 connected with a source of gas supply. This mandrel is preferably maintained at a temperature somewhat below visible redness or, at least, not sufficiently high to materially oxidize the tungsten wire under treatment. To shape the tungsten wire into a helix, it is only necessary to insert the wire in a slot 5 cut across the end of the mandrel, and to then slowly rotate the mandrel and wind the wire thereon. I will not attempt to explain why this heating of the tungsten changes it over from the brittle and non-ductile condition to the pliant state, but such is the case.

After the spiral is completed, it may be slipped off the mandrel and used in the lamp structure in any desired way. One manner of mounting is shown in Fig. 1, in which the tungsten spiral 6 is sealed directly in the end of the glass pedestal 7 carried by the lamp stem 8. The spiral serves as a support for the lamp filament 9. This figure is to be regarded as largely diagrammatic and as showing an embodiment which can be readily modified in a variety of ways. Fig. 2 shows a somewhat different arrangement in which a single tungsten spiral 10 serves for a plurality of filament loops. In this case the glass pedestal 11 of the lamp carries a glass sleeve 12 which is free to move up and down the pedestal except for the action of the tungsten spring 10 by which it is forced outward toward the end 11.

2
of the pedestal. This glass sleeve 12 carries a plurality of tungsten wires 13 having hooks 14 in their ends and serving as supporting arms for the lamp filaments. These wires may be of tungsten and may be bent into shape by use of the apparatus shown in Fig. 3.

When tungsten lamp filaments are running at exceedingly high temperatures, other elements of the lamp are heated thereby, and unless the elements are of proper material, they are liable to give up gases and impair the vacuum of the lamp or contaminate the material of the filament. A tungsten spring may be inclosed in a lamp without danger of undergoing change by heat from the filament, and so can be used in any position with safety. Further than this, a tungsten spring retains its elastic properties at very high temperatures, and therefore remains operative as a spring under conditions where less refractory metals would entirely fail.

Direct contact between the tungsten filament and the clean and unoxidized tungsten support offers no disadvantage, and in

fact, offers many advantages over those constructions in which the filament is liable to contamination by the material of the support or by gases liberated therefrom.

What I claim as new, and desire to secure by Letters Patent of the United States, is,—

1. The combination with a refractory metal filament of supporting means therefore by which it is yieldingly supported comprising a coiled spring of tungsten engaging with the filament.
2. The combination of a tungsten lamp filament and a resilient support therefor consisting of tungsten.
3. The combination with a tungsten filament of supporting means therefor comprising a bent wire of tungsten engaging with the filament.

In witness whereof, I have hereunto set my hand this 12th day of June, 1907.

WILLIS R. WHITNEY.
